United States Patent Office

Des. 187,250
Patented Feb. 16, 1960

187,250

COMBINED PEN AND PAPER HOLDER

Allan Robinson, Boston, Mass.

Application August 15, 1958, Serial No. 52,214

Term of patent 3½ years

(Cl. D74—1)

The figure on the drawing is a perspective view of a combined pen and paper holder showing my new design.

I claim:

The ornamental design for a combined pen and paper holder, substantially as shown.
